UNITED STATES PATENT OFFICE

99,438

DESIGN FOR A COOKING STOVE

Maurice G. Klemme, Belleville, Ill., assignor to
Eagle Foundry Company, Belleville, Ill., a cor-
poration of Illinois

Application November 23, 1935, Serial No. 59,716

Term of patent 3½ years

To all whom it may concern:

Be it known that I, Maurice G. Klemme, a citizen of the United States and a resident of the city of Belleville, in the county of St. Clair and State of Illinois, have invented a new, original, and ornamental Design for a Cooking Stove, of which the following is a specification.

In the accompanying drawing, which forms part of this specification,

Fig. 1 is a front perspective view of a cooking stove with the top in closed position showing my new design; and

Fig. 2 is a similar view of said stove with the top thereof shown in opened position.

The ends or sides of the stove not shown are substantially plain and the base is like the base shown in the two figures on the drawing.

I claim:

The ornamental design for a cooking stove, as shown and described.

MAURICE G. KLEMME.
